UNITED STATES PATENT OFFICE.

HARRY S. FOLGER AND JOSEPH C. JULIEN, OF CHICAGO, ILLINOIS, ASSIGNEES, BY
DIRECT AND MESNE ASSIGNMENTS, TO R. D. SWISHER MANUFACTURING COMPANY,
OF CHICAGO, ILLINOIS, A CORPORATION OF ILLINOIS.

HAND-STAMP.

1,301,926.

Specification of Letters Patent. Patented Apr. 29, 1919.

Application filed July 27, 1916. Serial No. 111,579.

To all whom it may concern:

Be it known that we, HARRY S. FOLGER and JOSEPH C. JULIEN, citizens of the United States of America, and residents of Chicago, county of Cook, and State of Illinois, have invented certain new and useful Improvements in Hand-Stamps, of which the following is a specification.

Our invention relates to hand stamps and has for its object the provision of a shield which is readily attached to the stamp and securely held in place.

Figure 1 is a side elevation of a dating stamp having the shield secured in position;

Fig. 2 is an end elevation;

Fig. 3 is an elevation of the dater with the shield in central longitudinal section; and

Fig. 4 is an enlarged perspective view of the shield detached.

The dater consists of a frame 10, bands 11, adjusting wheels 12, a handle 13 held in place by a screw 14 secured to the frame, and other parts well known. These parts, including those just mentioned in detail, are the same as those in ordinary dater's with the exception that the lower ends of the frame 10 are provided with lugs 15.

The shield or guard 16 is a U-shaped piece having slots 17, notches 18, and a hole

19 through which passes the screw 14. The slots 17 and notches 18 are to receive the wheels 12, which project through so that the bands 11 may be manually adjusted when the shield is in place.

To attach the shield, the handle 13 is removed and the shield slipped into place by passing the screw 14 through the hole 19, and then slipping the lower ends 20 of the shield under the lugs 15. The handle 13 is then returned to place where it acts as a nut to hold the shield in place by clamping it to the frame.

What we claim is:

1. The combination with a hand stamp having a frame, a screw secured thereto, and a handle held in place by the screw, of a U-shaped guard extending over the top of the frame and having a hole therein to receive said screw, said guard being clamped to said frame by said handle acting as a nut.

2. The combination with a hand stamp having a frame provided with lugs, and a handle, of a guard consisting of a single piece of metal clamped to the frame by the handle and having its ends held in place by said lugs.

HARRY S. FOLGER.
JOSEPH C. JULIEN.
